JAMES BRYANT WHITMORE AND JOHN EBLING FERGUSON, OF BLOOMFIELD, NEW JERSEY, ASSIGNORS TO WESTINGHOUSE LAMP COMPANY, A CORPORATION OF PENNSYLVANIA.

SEALING-IN MACHINE FOR TIPLESS LAMPS.

Application filed August 1, 1921. Serial No. 488,754.

To all whom it may concern:

Be it known that we, JAMES BRYANT WHITMORE, a citizen of the United States, and a resident of Bloomfield, in the county 5 of Essex and State of New Jersey, and JOHN EBLING FERGUSON, a citizen of the United States, and a resident of Bloomfield, in the county of Essex and State of New Jersey, have invented a new and useful 10 Improvement in Sealing-In Machines for Tipless Lamps, of which the following is a specification.

This invention relates to lamp making machinery and more particularly to machines which operate to effect the consolidation of lamp parts as, for example, the mounts and the bulbs in the manufacture 15 of incandescent electric lamps.

An object of the invention is to automatically align and support several of the component parts of a lamp for the purpose of consolidation.

Another object is to provide a machine which will automatically adjust one lamp 20 part in a given relation to another part and operate to perform this function in an expeditious and efficient manner.

A further object is to provide a mechanism which will automatically change the 25 relative positions of connected parts of a lamp while the union between the parts is in a pliable state.

Other objects will manifest themselves 30 upon a reading of the following description.

Machines for sealing mounts into bulbs, for the purpose of producing electric 35 lamps, are well known in the art as sealing-in machines. One type of such machines in general use employs a rotary conveyor upon which a plurality of sealing-in heads are rotatably mounted. These heads comprise means for supporting bulbs and suitable mechanism for holding the lamp 40 mounts, which mechanism is termed the mount holder. In practice the operator secures a mount in the mount holder, and in certain types of lamps it is a prerequisite to locate the light source, i. e. the 45 filament, in the plane of the maximum diameter of the bulb. This positioning of the light source necessitates certain structural requirements in the mechanism of a sealing-in head.

After a mount is positioned and a bulb 55 has been placed in proper relation thereto, the carrier or conveyor is rotated a given distance and portions of the bulb are subjected to heat by means of a series of burners which render plastic portions of the 60 neck of the bulb and the mount, thereby effecting the consolidation of the bulb to the flared portion of the mount. After the consolidation of the mount to the bulb and while the glass is in a semiplastic condition 65 it has been found necessary to pull down the mount, thus changing its position with respect to the bulb. The object of this relative downward movement of the mount being to prevent certain stresses which would be created if the material were permitted to solidify without the mechanical stretching thus caused, and this downward movement is, in the art, commonly termed 70 the "pull down." Heretofore, the pull-down operation has been accomplished 75 manually. A novel form of gripping mechanism is shown herein for properly securing an exhaust tube of a lamp mount, which mechanism is more clearly illustrated 80 and claimed in our copending application, Serial No. 530,149, filed January 18, 1922.

The present invention provides a sealing-in head which in addition to automatically adjusting a bulb in proper relation to a 85 mount holder also automatically effects the above mentioned pull-down so that upon a complete cycle of a conveyor, a lamp is ready, with the light source properly located, to be removed by the operator for 90 the assembly in the head of another mount and bulb.

Lamp bulbs or blanks are commonly manufactured with an elongated neck and it is the practice to provide the necks of 95 bulbs with an annular collar for the purpose of more readily severing the lower or surplus portion of the neck from the bulb to facilitate the handling of the same. This operation of breaking off the lower portion of the bulb is known as the "crack-off."

In the present invention the crack-off operation may be eliminated and the bulb 100 handled with its full length of neck and an operator may, without undue attention, drop a bulb over a mount, permit the lower end of the bulb to rest upon a shelf or collar and

then actuate cooperative machine elements to pick up the bulb and adjust it in proper relation to the mount. The collar affords a temporary support for the bulb prior to its final adjusted position and avoids a certain amount of care upon the part of the operator, it being unnecessary to hold a bulb in position by hand until the mechanism has gripped it.

10 The invention will be more fully understood by reference to the accompanying drawings in which

15 Fig. 1 is a front view in elevation, with parts broken away, of a machine embodying this invention;

Fig. 2 is a side elevation, with parts broken away, of the machine;

15 Fig. 3 is a section taken on line III—III in Fig. 1, but on a larger scale;

20 Fig. 4 illustrates one style of a mount.

Fig. 5 is an enlarged plan view of Fig. 1;

Fig. 6 is an enlarged view taken on line V—V in Fig. 1, in the direction of the arrows;

25 Fig. 7 is a diagrammatic view of a bulb about to be engaged by gripping jaws;

Fig. 8 is a view similar to Fig. 7 after the jaws have gripped the bulb.

30 Fig. 9 is a diagrammatic view of a bulb secured by jaws but having the neck portion of shorter length;

Fig. 10 shows diagrammatically the relation of a cam surface to the heads.

35 The sealing-in head, as illustrated, consists of a casting having a central bearing and two laterally disposed vertical bearings in which spindles are rotatably mounted.

40 The spindles carry a pair of arms upon which centering and guide jaws are suitably positioned. The central bearing furnishes a means for supporting a mount holder and when a mount is inserted therein and a bulb placed in position, the jaw arms are closed to secure the bulb, after which the head is rotated until the fires play upon the proper portion and the bulb and the mount are sealed or consolidated with the stem.

45 Referring to the drawing the sealing-in head as illustrated consists of an upright or standard comprising a central enlarged portion 2 having upper and lower central bearings 3 and 4. Integral with and at each side of the upper central bearing are positioned lateral vertical bearings 5 and 6.

55 The standard is mounted rotatably in a hub 7 of a conveyor or spider 8, common to this class of machines and indicated in dotted lines in Figs. 1 and 2.

60 Within the central bearing is disposed a stem or mount holding tubular member which is actuated to secure the mount when the exhaust tube thereon is inserted into the said member. This mount holding member consists of a tube 9 which is adapted to be moved vertically and is provided with two

sets of three balls 11, the balls of each set being positioned in the wall of the tube and in a common plane. The balls are so disposed as to project on both sides of the wall of the tube 9, thus, if the exhaust tube of a 70 mount is inserted into the tube and between the balls, the balls may be brought to bear upon the exhaust tube.

An inward movement of the balls is, in the present construction, caused by the slight 75 upward movement of the tube 9 which movement brings the balls in contact with a tapered surface 12 of an intermediate sleeve 13 which causes an inward thrust of the balls, to secure the exhaust tube. Concentrically disposed with relation to the sleeve 13 and secured thereto is an outer sleeve 14 which serves as a casing and carrier for the gripping means and is reciprocable vertically in the combined bearings 3 and 4.

80 The outer sleeve 14 is normally retained in a lower position through the action of a spring 15 disposed between a collar 16 secured to the sleeve 14 and a flange 17 of a driving pulley 18 secured to the bearing 4. 90 By arranging the gripping members or balls 11 in different transverse planes they may be actuated to provide a three point grip upon an exhaust tube at two places along its length. By this means a tube is held 95 in a vertical position and with its axial line substantially coincident with that of the head. The normal position of the sleeve 14 and consequently the stem gripping mechanism, is governed by a split stop collar 19 which may readily be adjusted by a screw 21.

95 As a means of supporting a bulb in position with respect to a positioned mount, a pair of arms 22 and 23 are provided, each 100 of which carries an upper jaw 24 and a lower jaw 25. These arms 22 and 23 are fastened to the upper ends of shafts 28 and 29 respectively, and are rotatable in the bearings 5 and 6. The lower ends of the shafts 28 110 and 29 extend below their bearings and the shaft 28 has fastened thereto a collar 31 provided with an extended portion or arm 32. The shaft 29 is provided with a rigidly attached crank 33 one arm 34 of which terminates in a finger piece 35. The opposite arm 36 of the crank is similar to the projection 32 to which it is connected by link 37.

115 A movement of the finger piece 35 rotates the shaft 29 and oscillates the jaw carrying arm 23, a simultaneous transmission of this movement is imparted to the arm 22 by the link 37, thus when the finger piece is moved toward the head the arms 22 and 23 which 120 carry the jaws 23 and 24 are rocked away from the axial line of the head and it is ready for the insertion of a bulb. When the finger piece is released the jaws automatically close, under the action of a spring 38 125 having one end secured to a pin 39 fastened 130

to the link 37 and the other end secured to a relatively stationary portion of the head by pin 40.

For the purpose of providing a support for the thumb of an operator during a compression of the finger piece 35 a button 41 is suitably positioned at the side of the bearing 3 opposite the finger piece. This button is secured to the head by a screw 42 the end 10 of which passes through the bearing 3 and serves as a key in a slot 43 disposed longitudinally of the sleeve 14, to prevent any rotary movement thereof but permitting its vertical travel.

15 A lamp mount 44 as shown in Fig. 4 is supported in the head by the insertion of its exhaust tube 45 into the tube 9 and between the balls 11. When the tube 9 of the mount holder is in its lower position, as diagrammatically shown in Fig. 10, in which a track 46 having a cam face 47 is indicated, the lower end of the tube 9 rests upon the lower parallel surface of the cam and the balls 11 will then be in their lower position 20 removed from the bevel face 12 and free to permit the entrance of the exhaust tube. To position a bulb about the mount loosely disposed in the holder, the finger piece 35 is compressed until the jaws 24 and 25 are 25 opened sufficiently to admit the bulb which may readily be placed over the mount and be temporarily supported on the collar 19 (see Figs. 7 and 8.) The finger piece then being released the jaws 25 move toward and 30 engage with the tapered surface of the bulb, causing it to be thrust or ejected toward the jaws 24 which resist and limit the upward movement of the bulb. The bulb is in this manner automatically centered with its axis 35 substantially coincident with the axial line of the head, by a three point contact provided by the lower jaws 25 one of which has a V-shaped two point contact notch 47 suitably positioned; the other having a single-point contact 48. Fig. 9 shows a supported bulb which has had the lower end of the neck cracked off in the usual manner, a bulb of this character being equally applicable to the head.

35 When a mount and bulb has been suitably positioned in a head the conveyor or rotatable support is moved to bring the bulb in proper relation to the usual fires which render plastic a given portion of the bulb. 40 As the conveyor is rotated, the tube 9 moves up the inclined cam face until the balls 11 have gripped the exhaust tube by reason of their contact with the bevel surface 12 of the tube 13 which is fastened to and is movable with the sleeve 14.

45 A slight travel of the tube 9 up the incline surface 47 is sufficient to secure the exhaust tube. A continued movement of the tube 9 up the incline causes the sleeve 14 to move upwardly in opposition to the spring

15; thus the collar 19 is raised above the upper end of the bearing 3, and the mount is moved upwardly until the filament is positioned at a point above the desired light center and at a distance above the required 70 final position equal to the amount of a subsequent pull down.

As the conveyor rotates and subjects the bulb to suitably disposed fires, the mount is maintained in its upper position inasmuch 75 as the end of the tube 13 is traversing the elevated surface of the track 46, however, as the head completes its rotation the downwardly inclined portion of the track or cam face 47 permits the entire mount holder to 80 take its initial or lower position, under the action of the spring 15, and automatically accomplish the pull down operation which is limited by the stop collar 19 contacting with the upper end of the bearing 3. Thus 85 the filament is accurately positioned in any predetermined location in the bulb in accordance with the adjustment of the collar 19. A continued movement of the conveyor or carries the end of the tube 9 from contact 90 with the cam face 47 and the tube is moved downwardly within the sleeve 14, through the agency of a spring 50 disposed between the lower end of the intermediate tube 13 and a collar 51 secured to the lower end of 95 the tube 9. This downward movement of the tube 9 thus serves to move the balls 11 from engagement with the tapered faces 12 and release the exhaust tube and consequently permit the free removal of the lamp 100 by the operator.

It is obvious that the upward movement of the mount will be determined and may be varied by the cam surface and that a convenient adjustment of the downward movement or pull down may be had by suitably positioning the collar 19.

When a mount and bulb are in their operative relative positions the conveyor is rotated to subject the bulb to heat, and thus render plastic such portions of the bulb necessary to effect a sealing or consolidation between the flare of the mount and the stem, and cause the severance of the lower portion of the bulb. Suitable means may be provided to supply added weight to the lower portion of the bulb which is termed the cullet to hasten its removal from the bulb. One such means being illustrated as 110 constituting a bifurcated member 52 adapted to swing on pivot 53 supported on the bracket 54 integral with the bearing 6. This member is swung about the pivot 53 and its two arms are adapted to rest upon the annular enlarged portion of the bulb. Thus when heat is applied and the material weakens the added weight of this member 115 serves to elongate the neck and sever the collar from the bulb.

120 In addition to the weighted member 52

it is common to force air upwardly through the stem holder, such air finding outlet through orifices 54' at the upper end of the tube 9 of the mount holder. This air supply is common to machines of this type and is conducted through the stem holder by means of passages 55 (see Fig. 3) disposed longitudinally between the walls of the sleeve 14 and tube 13. The interior of 10 the collar 16 at the lower end of the sleeve 14 is of conical shape and at one or more places about the track 46 air discharge outlets are provided from a pressure line and when the conical shaped collar registers 15 with such an outlet it provides for the guidance of air through the stem holder.

It will readily be understood that the 20 arms 22 and 23 and the jaws thereof will automatically position a bulb with its vertical axis coincident to that of a positioned mount. The jaws 24 and 25 are secured to the arms by screws 56 and 57 respectively and the jaws are slotted about the screw thus providing for their adjustment with 25 respect to the head. This permits the handling of a greater range of differently sized bulbs.

The embodiment of our invention as set 30 forth in the accompanying drawings provides an improved sealing-in head for use in the production of miniature tipless lamps. However, it is obvious that this head is applicable to the larger type of lamp and that the change, necessary to accommodate such lamps, will be of degree 35 and is contemplated by the present invention.

It will be further understood that this 40 invention may be embodied in many other forms than shown and described, and is not restricted to the precise form shown but intends to cover all changes and modifications within the spirit and scope of the appended claims.

45 What is claimed is:

1. A head for a sealing-in machine comprising a lamp-mount holder, means for temporarily supporting a bulb and means associated with said holder whereby said bulb may be adjusted and supported with 50 its axial line coincident to that of the mount holder.

2. A head for a sealing-in machine comprising a holder adapted to vertically support a lamp mount, means for temporarily supporting a bulb and means for lifting and supporting said bulb with the axial line thereof substantially coincident with that of 55 said mount.

60 3. A head for a sealing-in machine comprising, means for supporting a lamp mount in a vertical position, means for temporarily supporting a bulb, a pair of movable jaws adapted to be actuated in opposite directions 65 to lift and support said bulb with its axial

line substantially coincident to the axial line of the mount.

4. A head for a sealing-in machine comprising, means for supporting a lamp mount with its axial line coincident with the axial 70 line of the head, means for temporarily supporting a bulb, a pair of arms adapted to swing toward the axial line of the head to lift and support said bulb with its axis coincident with that of the head. 75

5. A head for a sealing-in machine comprising a mount holder, jaws movable toward the axial line of the head and adapted to support a bulb in a given relation to said mount holder and means for changing the 80 position of said mount with respect to said bulb.

6. A head for a sealing-in machine comprising a mount holder, jaws movable toward the axial line of the head and 85 adapted to support a bulb in a given relation to said mount holder and means for automatically changing the vertical position of said mount holder.

7. A sealing-in machine comprising a 90 lamp mount-holder, a bulb-support including a plurality of jaws, means for moving said jaws toward the axial line of said holder to secure a bulb, said bulb-support being capable of supporting a bulb in a 95 given relation to said mount-holder, means for securing a mount in said holder and means for moving said mount vertically within the bulb after said mount has been 100 united thereto.

8. A head for a sealing-in machine comprising means for vertically supporting a lamp mount, a pair of oscillatory arms, two jaws having their contact faces in different vertical planes disposed upon each arm, and means for operating said arms to secure a bulb in a predetermined position within the head. 105

9. A head for a sealing-in machine comprising a pair of oscillatory arms, two jaws disposed upon each arm, means for adjusting said jaws transversely of said head and means for operating said arms to secure a bulb in a predetermined position with respect to the head. 110

10. A head for a sealing-in machine comprising a lamp mount holder positioned on the axial line of the head, a pair of oscillatory arms, two jaws positioned upon each arm, means for operating said arms to secure a bulb in a predetermined position with respect to the said mount holder and means for varying the position of the mount with respect to said bulb. 120

11. A head for a sealing-in machine comprising a mount holder positioned on the axial line of the head, a pair of oscillatory arms, two jaws disposed upon each arm, means for operating said arms to adjust a bulb in predetermined position with 125 130

- respect to said head and means for automatically moving said holder vertically within said bulb.
12. A head for a sealing-in machine comprising a mount holder positioned on the axial line of said head, a pair of oscillatory arms, two jaws disposed upon each arm, means for operating said arms to adjust a bulb in predetermined position with respect to said head, means for automatically moving said holder within said bulb and adjustable means associated with said holder for limiting the movement thereof.
13. A head for a sealing-in machine comprising a lamp mount holder, a pair of oscillatory arms, an upper and a lower jaw positioned on each of said arms, means for operating said arms to bring them into engagement with a bulb in such a manner that one set of jaws causes a movement of the bulb until motion thereof is restricted by contact with the other set of jaws.
14. A head for a sealing-in machine comprising a lamp mount holder, a pair of oscillatory arms, an upper and a lower jaw positioned on each of said arms, means for operating said arms to bring them into engagement with a bulb in such a manner that the lower jaws cause an upward movement of said bulb until arrested by contact with said upper jaws.
15. A head for a sealing-in machine comprising a lamp mount holder, a pair of oscillatory arms, an upper and lower jaw adjustably positioned upon each of said arms, means for operating said arms to move said lower jaws into engagement with a tapered portion of a bulb whereby said lower jaws cause an upward movement of said bulb and the upper jaws limits said movement.
16. A head for a sealing-in machine comprising a lamp mount holder, a pair of oscillatory arms, an upper and lower jaw positioned on each arm, said lower jaws adapted to provide an initial engagement with the tapered portion of said bulb and means for effecting a movement of said jaws toward the bulb whereby the bulb is forced upwardly and in contact with the upper jaws of the arms.
17. A head for a sealing-in machine comprising a lamp mount holder, a pair of oscillatory arms, an upper and lower jaw positioned upon each of said arms, means for operating said arms to bring the said lower jaws into engagement with a tapered portion of the bulb whereby said lower jaws cause a movement of said bulb and the upper jaws limit said movement and means for effecting a vertical movement of said lamp mount holder.
18. A head for a sealing-in machine comprising a lamp mount holder, a pair of oscillatory arms disposed in operative relation to said holder, each of said arms being provided with a centering jaw and a guide jaw, means for operating said arms to bring said jaws into engagement with a bulb whereby said bulb is centered with respect to the holder and retained from lateral movement.
19. A head for a sealing-in machine comprising a lamp mount holder, a pair of oscillatory arms disposed in operative relation to said holder, each of said arms being provided with a centering jaw and a guide jaw, means for operating said arms to bring said jaws into engagement with a bulb whereby said bulb is positioned with its axial line substantially coincident to the axis of said holder and means for automatically effecting a vertical movement of said holder.
20. A head for a sealing-in machine comprising a lamp mount holder, a temporary support for a bulb, means adapted to engage with and lift said bulb from said support.
21. A head for a sealing-in machine comprising a lamp mount holder, a temporary support for a bulb, means adapted to engage with and lift said bulb from said support and means for automatically effecting a vertical movement of said lamp mount holder.
22. A head for a sealing-in machine comprising a lamp mount holder, a temporary support for a bulb, means for lifting said bulb from said support and means for limiting the upward movement of said bulb.
23. A head for a sealing-in machine comprising a lamp mount holder, a temporary support for a bulb, means for lifting said bulb from said support, means for limiting the upward movement of said bulb and means for automatically effecting the upward movement of said lamp mount holder.
24. A head for a sealing-in machine comprising a lamp mount holder, a temporary support for a bulb, means for elevating and maintaining said bulb in a predetermined position with respect to said holder.
25. A head for a sealing-in machine comprising a temporary support for said bulb, a pair of movable arms, two jaws secured to each arm, means for operating said arms to bring one pair of said jaws in contact with a tapered portion of said bulb whereby said pair of jaws tends to cause an upward movement of said bulb and the remaining pair of jaws limits the upward movement of said bulb.
26. A head for a sealing-in machine comprising a lamp mount holder, a temporary support for a bulb, means for elevating and maintaining said bulb in a predetermined position with respect to said holder and means for automatically actuating said holder to move the mount vertically with respect to said bulb.
27. A head for a sealing-in machine comprising a lamp mount holder, a temporary support for a bulb, a pair of movable arms,

two jaws secured to each arm, means for operating said arms whereby one pair of jaws engages with the tapered portion of said bulb and effects its upward movement 50 and the other pair of jaws contact with and limit said upward movement and means for effecting a vertical movement of said holder.

28. A head for a sealing-in machine comprising an adjustable temporary support for 10 said bulb, a pair of oscillatory arms, means for operating said arms, an upper and a lower jaw secured to each arm, said lower jaws being positioned to engage with the tapered portion of a positioned bulb whereby 15 a closing of the jaws tends to eject the bulb upwardly and move it in contact with the upper jaws.

29. A head for a sealing-in machine comprising an adjustable temporary support for 20 said bulb, a pair of oscillatory arms, means for operating said arm, an upper and a lower jaw secured to each arm, said jaws being adjustable transversely of the head, said lower jaws being positioned to engage with the 25 tapered portion of a bulb whereby an actuation of the arms causes the lower jaws to engage with the bulb and thrust it upwardly until the upper portion of the bulb contacts with the upper jaws.

30. A head for a sealing-in machine comprising a mount holder, a pair of oscillatory jaws movable toward the axial line of the holder whereby a bulb may be supported with its vertical axis coincident with that of 35 the mount, means for uniting the mount to the bulb and means for automatically effecting a pulling down of the mount.

31. In a sealing-in machine, the combination of a rotatable support, a plurality of 40 heads mounted thereon, means for securing a lamp mount in each of said heads, means for positioning a bulb in a given relation to said mount and means for changing the relative positions of said mount and bulb during 45 a movement of the support.

32. In a sealing-in machine, the combination of a rotatable support, a head rotatably mounted thereon, means for holding a

mount, means for temporarily supporting a bulb, means for automatically adjusting said bulb to a predetermined position with respect to the mount, means for consolidating said mount and bulb and means for changing the relative position of said mount subsequent to said consolidation.

33. In a sealing-in machine, the combination of a rotatable support, a plurality of heads mounted thereon, each head having a holder for a lamp mount, means for temporarily supporting a bulb in a given relation to said mount, means for automatically adjusting said bulb to bring the axial line thereof coincident with the axial line of the mount, means for securing said mount in said holder, means for effecting an upward movement of said mount within said bulb, means for rendering plastic given portions of said mount and bulb to cause a union therebetween, means for moving said mount downwardly subsequent to the said uniting 70 operation and previous to the solidification of said plastic portion, means for automatically releasing said mount and means for releasing said bulb.

34. A head for a sealing-in machine comprising a plurality of contact members disposed in pairs, means for temporarily supporting a bulb, means for engaging the bulb with one pair of said members to cause a bulb to move therebetween and engage with 80 another pair of said members to center the bulb within the head.

35. A head for a sealing-in machine comprising two pairs of jaws, each pair disposed in a different plane, means for operating said jaws to cause one pair thereof to grip the tapered portion of a bulb disposed therebetween, whereby the bulb is moved until another portion thereof makes contact with another pair of jaws to center the 90 bulb within the head.

In testimony whereof, we have hereunto subscribed our names this 29th day of July 1921.

JAMES BRYANT WHITMORE.
JOHN EBLING FERGUSON.
